US00D870722S

(12) **United States Design Patent** (10) Patent No.: **US D870,722 S**
Shen et al. (45) Date of Patent: **** Dec. 24, 2019**

(54) **MOBILE COMPUTING DEVICE**

(71) Applicant: **SYMBOL TECHNOLOGIES, LLC**,
Lincolnshire, IL (US)

(72) Inventors: **Mu-Kai Shen**, Taipei (TW); **Edward M. Voli**, East Setauket, NY (US);
Travis Baldwin, Medford, NY (US)

(73) Assignee: **Symbol Technologies, LLC**, Holtsville,
NY (US)

(**) Term: **15 Years**

(21) Appl. No.: **29/653,854**

(22) Filed: **Jun. 19, 2018**

Related U.S. Application Data

(63) Continuation of application No. 29/581,696, filed on Oct. 20, 2016, now Pat. No. Des. 823,852.

CLAIM

We claim the ornamental design for a mobile computing device, as shown and described.

DESCRIPTION

FIG. 1 is a front perspective view of a mobile computing device showing our new design;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

Broken lines depict portions of the mobile computing device that form no part of the claimed design.

1 Claim, 7 Drawing Sheets
